UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A KNOB AND LATCH ESCUTCHEON-PLATE.

SPECIFICATION forming part of Design No. 17,338, dated May 10, 1887.

Application filed March 21, 1887. Serial No. 291,777. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for a Knob and Latch Escutcheon-Plate, of which the following is a specification, reference being had to the accompanying drawing, forming part thereof.

10 The only figure of said drawing is a front elevation of my newly-designed escutcheon-plate for a door latch and lock.

Surrounding the knob-escutcheon A is a plain surface whose general form is rectangular, above and below which there is a raised bar or band, a, surrounding the central panel. 15 This bar or band curves inwardly from each corner of the rectangular plain surface of the knob-escutcheon, and then extends in right 20 lines. Inside the band a, above the knob-escutcheon, there are conventional leaves or branches connected by a transverse bar, said ornaments being on a roughened ground. Immediately below said escutcheon A the orn- 25 namental figure is in the form of a ring with a looped bar in four loops, through which the ring passes. Below this there is a transverse bar, b, extending across the central panel at the top of the lock or key-hole escutcheon B.

This lower part of the central panel is orna- 30 mented by lines and a series of rectangular depressions contiguous to the border band. Outside of the central panel is the main panel, having a plain band or border, c, surrounded by a series of circles and ovals, d, and another 35 plain band, e, having a beveled edge. The space outside of the central panel that is inclosed by the border ornaments c d e is mainly ornamented by groups of leaflets and scroll-work, the leaflets having concave faces marked 40 with transverse lines.

I claim—

1. In a design for a knob and lock escutcheon, the design for the central panel herein shown and described, the same consisting of 45 the border-band a, curving outwardly at four points, the connecting plain face between the curved portions of said band and the several ornaments inclosed by said border-band.

2. The design for a knob and lock escutcheon 50 herein shown and described, the same consisting of the central and main panels, with the space between the borders thereof ornamented by groups of leaflets and scroll figures.

GEORGE S. BARKENTIN.
